UNITED STATES PATENT OFFICE.

JOHN J. LEE, OF BROOKLYN, NEW YORK, ASSIGNOR TO JOSEPH R. ROTHSCHILD,
JEROME B. BEHREND, AND CLAUDE COLLER, COMPOSING THE FIRM OF BEHREND
& ROTHSCHILD, OF NEW YORK, N. Y.

ELASTIC DOLL.

Application July 30, 1923. Serial No. 654,591.

To all whom it may concern:

Be it known that I, JOHN J. LEE, a citizen of the United States of America, residing at Brooklyn, Kings County, State of New York, have invented certain new and useful Improvements in Elastic Dolls, of which the following is a specification.

The invention relates to toy figures, such as dolls or the like and in particular to the 10 inflatable rubber type.

A particular object of the invention is to provide a doll, the body, arms and legs of which shall be made of heavier or thicker rubber than the head portion so that the latter may expand more rapidly and entirely out of proportion to the expansion of the former.

A further object is to provide a figure of this character in which a double sound will 20 be made when the body of the doll is squeezed and released, and also the head portion will become enlarged when the body portion is squeezed.

Referring to the drawings wherein I have 25 shown one embodiment of my invention in the form of a toy figure;

Figure 1 is a face view of the doll showing the same after inflation, the relative size of head and body being illustrated; and;

30 Figure 2 is a partial section taken through the doll while inflated showing the check valve and sound producing device which forms the neck of the figure.

Referring to the drawing in detail, 5 indicates the inflatable body portion, having inflatable arms 5^a and inflatable legs 5^b, and 6 the head portion of a doll figure constructed in accordance with my invention. The head portion 6 it will be noticed is made of a thinner rubber than the body portion 5 and is closed at the neck 7 by the insertion therein of a cylindrical block 8 around the center of the periphery of which is formed a groove 12 in which the 40 edge of the neck portions of the head is held by its own elasticity.

This block 8, which may be of wood, is provided with a bore 9 over the ends of which are disposed the metallic reed-like 45 lips 10 which are fastened to the block in any suitable manner so that the loose ends

thereof which overlie the bore 9 will vibrate when air passes through the bore and cause a sound to be emitted. This occurs when the body is squeezed and then released, because the head material is thinner and the air is forced through the bore and causes vibrations of the lips 10 as well as enlargement of the head of the figure.

In order to hold the figure inflated I provide in the head thereof a check valve 11, which allows the air to be blown into the figure and prevents its escape therefrom; the same being of any well known type which may be opened to cause deflation.

The body portion 5 is provided at its upper edge with a heavy integral rubber ring 14 which fits into the groove 12 and keeps the parts of the figure together and provides an air-tight connection.

It will be noted that I have provided a figure in which the head expands more rapidly than the body giving to the figure a distorted yet pleasing appearance. Also when the same is squeezed it will produce, 70 for the amusement of children, a crying or other similar sound.

It is to be understood that the form of figure may be varied to animals, fish or the like and that any reed arrangement may be 75 supplied to produce a multiplicity of different sounds.

Having described my invention what I claim therefore is:

An inflatable toy comprising a head and 80 a body portion, the body having inflatable arm and leg portions, the head being made of relatively thinner material whereby it will expand more rapidly than said arm and leg portions, a check valve in the head 85 portion, a block between said head and body portions having a peripheral groove and a passage-way therethrough, a vibratory element at each end of said passage-way whereby a sound will be emitted upon passage of 90 air in either direction through said passage-way and a ring integrally formed on the upper edge of said body portion for holding the head portion and the body portion in air-tight relation in the groove in said 95 block.

JOHN J. LEE.
